UNITED STATES PATENT OFFICE.

ALBERT JOHN FREDERICK LEE, OF MONTREAL, CANADA.

IMMERSIBLE SALVAGE VESSEL.

1,388,729.

Specification of Letters Patent. Patented Aug. 23, 1921.

Application filed August 22, 1919. Serial No. 319,115.

To all whom it may concern:

Be it known that I, ALBERT JOHN FREDERICK LEE, a subject of the King of Great Britain, residing in Montreal, Canada, have invented certain new and useful Improvements in an Immersible Salvage Vessel, of which the following is a specification.

A submersible vessel has been described in which a central tunnel of an inverted 10 U section forms a chamber inclosed as to its sides and roof and open below to the sea water. A smaller vessel can be inclosed in this tunnel, a cushion of air at the top and sides preventing contact between the inner 15 and outer vessels. The outer vessel can at any time be submerged below the surface by admitting water into suitably arranged compartments.

The present invention relates to the construction and use of a vessel of this type for salvaging wrecks.

The objects of this invention are to provide a vessel which is readily adapted to operate in different depths of water, which, 25 as a unit, includes apparatus and facilities for the complete salvage operation, and which will permit of such operations being carried on in a minimum of time and with a maximum degree of safety to the operatives. 30 With these and other objects in view my invention consists in certain features of structure, combination and relation which will be more fully set forth hereinafter.

In the accompanying drawing, Figure 1 35 is a section of the salvage vessel inclosing the wreck, Fig. 2 is a sectional elevation of the stern showing the means for raising the gates; Fig. 3 is a sectional plan corresponding to Fig. 2 showing means for securing 40 the gates in the closed position, Fig. 3^a shows a detail of the means for securing the gate at the end of the vessel in closed position, Fig. 4 shows a detail of the means for withdrawing water from a sound hold 45 of the wreck; Fig. 5 shows the floating air lock.

Referring to Fig. 1, A is the salvage vessel and B a wreck lying on the sea bed and over which the salvage vessel has been dropped. The upper deck of the vessel A is shown at 1 and the lower deck at 2; 50 3 is the engine room, 4 the depending legs or sides of the salvage vessel forming the sides of the tunnel 5. The legs or sides 4 55 are divided into compartments which can be filled with water acting as ballast in or-

der to submerge the vessel and can be emptied to provide the required buoyancy; 6 are reserve buoyancy or compensating tanks. Pig-iron or other suitable ballast 60 is provided at the bottom of the legs. 7 is a tower extending mid-ships from the deck 8 over the engine room above the sea level. The struts of the tower are formed as trunks 7^a respectively supplying air to compressors 65 and to the various parts of the ship and serving for the removal of contaminated air. A platform 9 is provided at the top of the tower and a lift 10 serves as means of access to the vessel.

The submersible vessel is hauled down by means of winches 13 on the salvage vessel which are operated by suitable mechanism (not shown) and cables 11 previously attached by divers to the wreck. Rams 12 are 70 provided for the purpose of raising the wreck by means of cables (not shown in the drawings) attached to the hull in subsequent operations. Cabins for the accommodation of the crew are shown at 14 and air lock passages 15 enable access to be obtained to the tunnel 5.

A water-tight gate or door 16 is provided at the end of the vessel, e. g., the stern and has a horizontal hinge connection 17 with 75 the vessel so as to be raised by a crane 18 into the horizontal position, shown by the dotted lines in Fig. 2, or lowered into the vertical position shown by the full lines. A similar door may be and usually is provided at the bow of the vessel, although permanent plating may be substituted for one of the doors.

As shown in Figs. 2, 3 and 3^a the door is secured in the closed position by sliding 95 wedges 19 provided with racks 20 engaged by pinions 21 keyed to a spindle 22 operated by suitable turning gear. The wedges 19 force the door against a rubber seating 23 and a jamb 24. The door is also held 100 against being forced open by the pressure of air inside the tunnel by ropes or chains 25 passing over pulley blocks 26 and 27 secured respectively to the door and to the walls of the tunnel.

The water from any sound hold can be expelled by fitting a pipe 28 (Fig. 4) into the hold and connecting it by a cock or valve 29 with a chamber 30 provided in the vessel A. 31 and 32 are cocks or valves connecting the chamber, respectively, with the air space in the tunnel and with the atmos-

phere. By closing 32 and opening 31 the chamber 30 will be filled with air at atmospheric pressure and water will flow through the pipe 28 into the chamber 30 from which it can be expelled by suitable means.

Pipes 33 opening into the tunnel at varying depths and connected through cocks or valves 34 to a common pipe 35 enable the air in the tunnel, if at any time it is contaminated, to be exhausted and replaced by fresh air. The pipes 33 are made of different lengths in order that they may serve to exhaust gases of different densities which may be formed in the tunnel and which lie at different levels, the heaviest and usually the most dangerous of these gases usually being at the lowest level. On account of the large volume of air contained in the tunnel, it may, under some conditions, be undesirable to exhaust all of the air contained in the tunnel. In such cases only the longer pipes may be utilized in order to remove the heaviest and more dangerous gas which, as stated, is at the lowest level. The pipe 33 may also be used, by exhaustion of the closed air, to vary the water level within the tunnel.

A floating air lock (Fig. 5) 36 is connected by cables 37 to a salvage tender and 30 by cables 38 to the salvage vessel.

The bottom of the lock is tapered so as when hauled down to fit in a correspondingly tapered casing or trunk passage 39 provided in the pontoon deck of the salvage vessel. Rubber or other suitable packing 40 interposed between the adjacent sides of the casing and air-lock maintains a water-tight connection between the parts.

A ring 41 at the bottom of the air-lock 36 is provided with holes 42 registering with slots in a flange 43 of the casing; when the lock has been drawn into close contact with the casing, bolts 44 which are water-tight within the holes 42 are passed by operators 45 within the lock through the slots; the heads 45 of the bolts which are oval or rectangular are then turned round so as to engage below the flange and are tightened by nuts 46 to secure the lock to the casing.

50 A door 47 opening upward is provided in the air-lock and a door 48 opening inward in the trunk, so that the workmen can enter and leave the vessel at any time.

If found advisable, the car may be formed 55 in sections adapted to move about vertical hinges so as to be more readily adapted to the sides of the wreck.

In the operation of salvaging a sunken vessel, the masts, funnels or other parts of 60 the wreck projecting any considerable distance above the decks are removed by dyna-

mite or other suitable means and attachments are made to the wreck at various points to which hawsers are secured and the free ends of the hawsers buoyed, this 65 operation being carried out by divers in the usual manner. The salvage vessel is then brought over the wreck where it is anchored, and the buoyed hawsers are picked up and secured to the winches. Water is then admitted to the ballast tanks of the vessel until buoyancy is reduced to a small amount, in case of a large vessel to about one hundred tons. The winches are then actuated, the hawsers being wound upon the drums, and 70 the vessel hauled down so as to inclose the wreck. The end doors are then lowered and secured and the salvage vessel is then in a position to act as a large diving bell, the air compressors driving the water out of the 75 tunnel and allowing the salvage operations to be carried on in the water-free space.

Where the vessel to be salvaged lies in comparatively deep water, the wreck may be lifted and carried to shallower water 80 where the operators can work for a longer period and the repairs be executed more rapidly.

Having thus described the nature of the said invention and the best means I know 90 of carrying the same into practical effect, I claim:

1. A submersible salvage vessel comprising a central tunnel approximately of an inverted U section, forming a chamber 95 inclosed above and at the sides and open below to the sea water, the said chamber being adapted to be closed at at least one end by a vertical door pivoted about horizontal hinges, and means for securing the door in 100 the closed positions including a jamb and a resilient seating therefor, wedges for forcing the door against the jamb, and means for sliding said wedges into operative positions.

2. A submersible salvage vessel comprising a central tunnel approximately of an inverted U section, forming a chamber 110 inclosed above and at the sides and open below to the sea water, the said chamber being 115 adapted to be closed at at least one end by a vertical door pivoted about horizontal hinges, and means for securing the door in the closed positions including a jamb and a resilient seating therefor, wedges for forcing the door against the jamb, racks on the wedges and pinions gearing with said racks.

In testimony whereof I have signed my name to this specification.

ALBERT JOHN FREDERICK LEE.
